UNITED STATES PATENT OFFICE.

EDWARD NICHOLAS GULICH, OF WEST HAMPSTEAD, LONDON, ENGLAND.

ROTARY PUMP OR MOTOR APPLICABLE ALSO AS A FLUID-METER.

SPECIFICATION forming part of Letters Patent No. 726,907, dated May 5, 1903.

Application filed May 5, 1902. Serial No. 105,997. (No model.)

To all whom it may concern:

Be it known that I, EDWARD NICHOLAS GULICH, a subject of the King of Great Britain and Ireland, and a resident of 94 Lyncroft 5 Gardens, West Hampstead, in the county of London, England, have invented an Improved Rotary Pump or Motor Applicable also as a Fluid-Meter, of which the following is a specification.

10 This invention relates to a rotary pump or motor, also applicable for use as a meter for measuring fluids, of the type in which a drum or disk carrying hinged vanes turns within a casing against which the vanes bear. My 15 construction provides an apparatus of this kind which can be made in a very inexpensive manner, is easily repaired, and possesses great efficiency.

In order that this invention may be more 20 readily understood, reference is had to the accompanying sheet of drawings, in which—

Figure 1 is an elevation of the apparatus with one side of the casing removed. Fig. 2 is a cross-section with part of the drum removed, and Fig. 3 shows a modified arrangement of the wings or vanes.

The rotating drum A is concentric with the casing B, both being cylindrical, and in order to close the vanes C upon the drum at one 30 point of their travel I provide a metal strip D, curved to form a crescent-shaped division in the chamber and fixed to a projecting block or abutment b between the inlet and outlet ports b'. This strip D is formed with 35 holes or openings d, extending toward each end, so that the water flows into or out of the cylinder through a considerable portion of the circumference, the curved strip forming chambers d' at each side of the central 40 division, into which the ports b' open. As the casing and drum are concentric, the compartments between the hinged blades or vanes remain the same size through a considerable portion of the revolution, contracting or 45 expanding only while the water is passing in or out. As the vanes pass the central division or block they are completely closed down upon the drum, so that no liquid can pass from one side to the other across the division. 50 I also provide the drum or disk A with a shallow annular groove or channel a, so that a

space is left behind each vane when closed, this channel preventing any dirt or grit which may enter the apparatus interfering with the complete closing of the vanes. A small body 55 of water is also carried along by each vane when closed, owing to this channel, and this assists in providing a water-tight joint for the vanes, more especially serviceable in starting the pump, as this pump can be started without difficulty when empty, there being no necessity for priming.

The vanes C are hinged by solid beads c, at their ends dropping into correspondingly-formed channels in the periphery of the 65 drum.

In order to make the apparatus reversible, so that it will act in both directions, alternate vanes may be placed in a reverse manner, as shown in Fig. 3. This also provides 70 a brake action, as any slip of the water past the rotating drum would act to raise the normally inoperative vanes and bring them into action.

If used as a meter, it is to be understood 75 that the usual counting mechanism is to be attached to the shaft carrying the drum A; but the apparatus is more especially intended as a pump or water-motor.

What I claim as my invention, and desire 80 to secure by Letters Patent, is—

1. In a rotary pump, motor or meter having a rotating drum within a casing carrying hinged vanes expanding against the casing, a shallow groove a extending completely 85 around the periphery of the drum behind the hinged vanes, substantially as and for the purposes specified.

2. A rotary pump, motor or meter, having a rotating drum within a casing, hinged vanes 90 upon the rotating drum expanding against the casing and arranged to open alternately in the opposite directions, and means for closing the vanes against the drum, substantially as herein described and shown. 95

In witness whereof I have hereunto set my hand in the presence of two witnesses.

EDWARD NICHOLAS GULICH.
